UNITED STATES PATENT OFFICE.

GEORGE S. BLAKESLEE, OF CHICAGO, ILLINOIS.

WASHING-MACHINE.

1,313,455.

Specification of Letters Patent. Patented Aug. 19, 1919.

Application filed February 9, 1916. Serial No. 77,241.

To all whom it may concern:

Be it known that I, GEORGE S. BLAKESLEE, a citizen of the United States, and a resident of Chicago, in the county of Cook, State 5 of Illinois, have invented certain new and useful Improvements in Washing-Machines, of which the following is a specification, reference being had to the accompanying drawings.

10 My invention relates to washing machines, and has for one of its objects the provision of a new and improved arrangement of forwarding means for carrying articles through sprays or streams of water for cleaning 15 them. It is one of the objects of my invention to provide in a machine of this type removable and interchangeable supports along which the articles to be cleaned are adapted to be carried by the conveyer means, where- 20 by supporting means can be provided as desired for properly supporting any of a variety of shapes and forms of castings or other articles to be cleaned. It is another object of my invention to provide in a de- 25 vice of this type a new and improved form of tank having such conformation as to render it easily cleaned when desired. It is another object of my invention to provide a new and improved arrangement comprising 30 a two-part tank together with means for carrying the lower portion of the carrying chain over the partition between the two sections of the tank without interference therewith. It is another object of my invention 35 to improve washing machines in sundry details hereinafter pointed out. The preferred means by which I have accomplished my objects are illustrated in the accompanying drawings and are hereinafter specifically described. That which I believe to be new 40 and desire to cover by this application is set forth in the claims.

In the drawings,—

Figure 1 is a side view of a washing machine embodying my improvements;

Fig. 2 is a view of the machine of Fig. 1 as seen from the opposite side;

Fig. 3 is a horizontal section, being taken substantially on line 3—3 of Fig. 1;

50 Fig. 4 is a longitudinal vertical section taken substantially on line 4—4 of Fig. 3;

Fig. 5 is a transverse vertical section, taken substantially on line 5—5 of Fig. 3;

Fig. 6 is an enlarged detail, being substantially a section taken on line 6—6 of Fig. 2;

Fig. 7 is an enlarged detail, being a fragmentary view showing the arrangement of the parts at the right hand end of the machine as shown in Fig. 3;

Fig. 8 is an enlarged detail showing the construction and arrangement of the driving means, being substantially a section taken on line 8—8 of Fig. 3;

Fig. 9 is an enlarged detail of one of the steam nozzles employed, being partially a section taken on line 9—9 of Fig. 8; and

Fig. 10 is an enlarged detail, being substantially a section taken on line 10—10 of Fig. 8.

Referring to the several figures of the drawings in which corresponding parts are indicated by the same reference characters,—

20 indicates a frame supporting a tank 21 comprising sections 22—23 (see Fig. 4) 75 on opposite sides of an intermediate wall or partition 24. As is clearly shown in Fig. 4, the bottom wall of each of the sections 22—23 is inclined downward for a considerable portion of its length toward the middle 80 of the tank, each section having a portion of considerably increased depth at its inner end.

Water is adapted to be supplied to the sections 22—23 of the tank through suitable 85 piping 25 from any suitable source, such piping being provided with valves 26 (see Fig. 2) for controlling the admittance of water.

Steam is adapted to be forced into the 90 water in the tank through piping 27 comprising valves 28 for controlling the entrance of the steam. The pipe 27 extends through the wall of the tank, as is best shown in Figs. 3 and 8, near the outer ends 95 of the sections 22—23, the inner ends being provided with improved steam nozzle mechanisms 29. As is best shown in Fig. 8, each steam nozzle mechanism 29 comprises three parts each in the form of a 100

nipple 30 having screw-threaded connection with the pipe 27 by means of a short pipe section 31 (see Fig. 9). Each nipple 30 is provided with a plurality of openings 32 and is provided at its outer end with a 105 pipe section 33 comparatively much larger than the section 31. The section 31 extends into the nipple 30 a short distance beyond the openings 32 therein. With the steam nozzle mechanism 29 below the level of the 110 water in the tank, steam is forced through the pipe 27 and through the several sec-

tions 31 into and through the nipples 30 and out through the sections 33. As the steam escapes from the end of the section 31, the cold water is drawn inward through 5 the openings 32 and is forced out with the steam through the pipe section 33, this operation serving to condense the steam, and to warm the water. I have found that by the use of a steam nozzle of this type the 10 water in the tank can be very quickly and easily warmed to the desired temperature. I have also found that this result is accomplished substantially noiselessly.

The tank is adapted to be drained by 15 means of piping 34 attached to the tank at two points near the bottom on opposite sides of the partition 24, suitable valves 35 being provided for controlling the escape of water. The pipe 34 is also connected 20 with the tank 21 near its ends by means of drain ports 36 whereby the level of the water in the tank is automatically regulated and limited to a predetermined maximum depth.

25 The tank 21 is provided with openings in its opposite ends adapted to be closed by valves or gates 37, best shown in Fig. 4, which are adapted to be drawn very tightly into engagement with edges of the openings for securely closing them. Each section of the tank is also provided with a manhole near its lowernost point at one side, which two manholes are closed by covers or gates 38 similar to the valves or 30 gates 37 (see Fig. 1). By means of the openings in the tank at the points indicated, provision is made for quick and easy cleaning of the tank when desired. By reason of the diagonal arrangement of the 40 bottom of the end portion of the tank the solid matter washed off of the castings or other articles being cleaned is caused to settle near the center of the tank from which point it can be easily removed.

45 The means provided for throwing water upon the articles being cleaned comprises two paddle wheels 39—40 fixedly mounted upon a shaft 41 within laterally-extending housings 42—43, the outer ends of which are 50 semicircular in shape, as best shown in Fig. 5. The shaft 41 and the paddle wheels 39—40 are driven in clockwise direction in Fig. 5 by means of a gear 44 mounted on said shaft meshing with a pinion 45 fixed 55 upon a shaft 46 journaled between said housings 42—43 and driven by a motor 47 by means of a belt 48 and pulleys 49—50, the motor 47 in the construction shown being mounted on top of the tank 21. By the 60 rotation of the paddle wheels 39—40 in clockwise direction in Fig. 5, a considerable amount of water is carried upward within the curved outer ends of the housings 42—43 and thrown with considerable 65 force to the right in Fig. 5 into the tanks

22—23. For the purpose of breaking up and scattering somewhat the water thrown by the paddle wheels 39—40 I have provided a plurality of downwardly-extending arms 51 spaced at intervals alongside the 70 paddle wheels 39—40 as is best shown in Fig. 4.

The means for conveying the articles to be washed past the paddle wheels 39—40 comprises an endless chain 52 revolving 75 about sprocket gears 53—54 fixedly mounted upon shafts 55—56, respectively, near opposite ends of the tank 21. The shaft 55 extends through the wall of the tank 21, as shown in Fig. 8, being provided on its outer end with a sprocket gear 57 by which the shaft 55 is adapted to be driven from another shaft 58 through the medium of a sprocket gear 59 mounted upon said shaft 58 and a sprocket chain 60 connecting the 80 gears 57 and 59. The shaft 58 in turn is adapted to be driven from the shaft 41 through the medium of intermeshing spiral gears 61—62 mounted upon the shafts 41 and 58 respectively. Upon the rotation of the shaft 41 for driving the paddle wheels 39—40 in clockwise direction in Fig. 5, the spiral gear 62 will be driven in clockwise direction in Fig. 10, causing a like rotation of the gear 57 in Fig. 2, serving to drive 90 the upper portion of the chain 52 toward the left in Fig. 4.

As is best shown in Fig. 10, the bearing for the shaft 41 in the end wall of the housing 42 comprises a sleeve 63 fixedly mounted 100 upon the said end wall. A housing comprising two members 64—65 is mounted upon the sleeve 63 about the gear 61 and the upper portion of the gear 62. A third housing member 66 is secured to the housing members 64—65 by bolts or in any other suitable manner. The housing member 66 is adapted to hold a supply of oil for keeping the gears 61—62 properly lubricated, and the housing members 64—65 are adapted to prevent objectionable splashing of the oil as 110 well as serving as a guard for the gears 61—62.

For enabling the lower portion of the chain 52 to pass freely over the upper edge 115 of the partition 24, I have provided diagonally-disposed slideways 67—68, the outer ends of which extend below the surface of the water in position to receive any downwardly-extending portion of the chain 52 for carrying it upward over the partition 24.

For slidably supporting the articles to be cleaned so as to enable them to be moved by the chain 52 lengthwise of the tank 21 past the paddle wheels 40—39, I have provided a plurality of longitudinally-extending bars 69 supported by transversely-extending bars 70 upon which the longitudinally-extending bars are fixedly mounted. As is best shown in Fig. 5, the bars 70 are 120

adapted to be of such a shape as to support the longitudinally-extending bars 69 in suitable position for providing an appropriate slideway for the particular type of casting 5 or other device being cleaned. In order to render the bars 69 removable, the bars 70 are removably supported in position, a removable support being provided in the construction shown by means of slotted 10 brackets 71 mounted upon the side walls of the tank from which the bars 70 are adapted to be lifted as desired. The transverse bars 70 also serve to support a channel iron 72 in which the upper length of chain is 15 adapted to slide. The chain 52 is provided with a plurality of hooks or brackets 73 secured at intervals therealong adapted to engage an article placed upon the longitudinally-extending bars 69 as they are 20 carried about with the chain 52, and to slide such article toward the left in Fig. 4 longitudinally of the tank 21.

With the section 23 of the tank filled with water of the proper temperature and provided 25 with a suitable soap, acid, or other suitable cleansing agent, and with the section 22 of the tank preferably filled with clean rinsing water, and with the paddle wheels 39—40 being driven by power from the motor 47, and with the chain 52 being driven as before indicated, a casting, such as the casting 74 shown in dotted lines in Fig. 5, is placed upon the ends of the longitudinally-extending bars 69, whereupon it 30 is carried forward by one of the hooks 73 of the chain 52 past the paddle wheels 40—39, receiving a thorough cleansing and subsequent rinsing as will be readily understood. Whenever it is desired to use the machine 35 for a different type of casting, the chain 52 is disconnected at some suitable point and the framework comprising the longitudinally-extending bars 69 and the transversely-extending bars 70 is lifted out of position 40 and another frame-work is substituted therefor having longitudinally-extending bars so positioned relative to each other as to provide an appropriate support for such casting.

50 I have found in practice that my device is highly efficient for cleansing castings such as are used in automobile construction, but I do not wish to restrict myself to this particular use for my machine.

55 So far as I am aware, I am the first in the art to provide a single chain for carrying castings or other articles to be washed along two tanks one adapted to contain a cleaning agent and the other adapted to contain rinsing water, and my claims are to be construed accordingly.

What I claim as my invention and desire to secure by Letters Patent, is—

60 1. In a washing machine, the combination 65 of two tank sections adjacent to each other

and separated by a partition rising above the level of the water in said sections, an endless conveyer adapted to travel over said two tank sections at or near the surface of the water in said tank sections, means above 70 the surface of the water in said tank sections and coöperating with the upper portion of said conveyer to conduct articles to be washed over said tank sections, and means for directing the lower portion of the conveyer over the partition between said tank sections.

2. In a washing machine, the combination of two tank sections adjacent to each other and separated by a partition rising above 80 the level of the water in said sections, an endless conveyer adapted to travel over said two tank sections at or near the surface of the water in said tank sections, and means comprising diagonally-disposed slideways 85 adapted to enable the lower portion of the endless conveyer to pass said partition.

3. In a washing machine, the combination of two tank sections adjacent to each other and separated by a partition rising above 90 the level of the water in said sections, an endless chain adapted to travel over said two tank sections at or near the surface of the water therein, said chain being provided with outwardly-extending brackets adapted 95 to engage an article to be cleaned for forwarding it, means above the surface of the water in said tank sections and coöperating with the upper portion of said chain to convey articles to be washed over said tank sections and means for directing the lower portion of said chain and the downwardly-extending brackets carried thereby upward over the partition between said two tank sections.

4. In a washing machine, the combination of two tank sections adjacent to each other and separated by a partition extending above the surface of the water in said sections, a slideway extending longitudinally 110 of said sections a short distance above the surface of the water therein, an endless chain adapted to travel along said slideway, being provided with outwardly-extending brackets adapted to engage an article to be 115 washed in position upon said slideway, and means comprising a diagonally-disposed slideway adapted to direct the lower portion of said endless chain and the downwardly-extending brackets carried thereby upward 120 over the partition between said two sections.

5. In a washing machine, the combination of a tank adapted to contain water, a slideway comprising a plurality of transversely-extending bars removably secured in position at or near the surface of the water in said tank, and a plurality of slide-bars mounted upon said transversely-extending bars, means at one side of said slideway for throwing water upon and across the ar- 125 130

ties resting thereupon and means for forwarding articles to be cleaned along said slideway.

6. In a washing machine, the combination of a tank adapted to contain water, a slideway comprising a plurality of transversely-extending bars removably secured a short distance above the level of the water in the tank, and a plurality of longitudinally-extending slide-bars fixedly secured to said transversely-extending bars, said transversely-extending bars being so shaped and the longitudinally-extending bars being so arranged as to provide a slideway of the desired conformation to suit the particular articles to be washed, means at one side of said slideway for throwing water upon the ar-

ties resting thereupon and means for forwarding articles to be cleaned along said slideway.

20

7. In a washing machine, the combination of a tank adapted to contain water, a plurality of pairs of oppositely-disposed slotted brackets secured upon the side walls of said tank, a plurality of transversely-extending bars adapted to be removably supported by said slotted brackets, a slide-bar secured to said transversely-extending bars a short distance above the surface of the water, means for throwing water upon and across said slide-bar, and means for forwarding an article to be cleaned along said slide-bar.
